UNITED STATES PATENT OFFICE.

JOHN A. WEBER, OF CHICAGO, ILLINOIS, ASSIGNOR OF FOUR-FIFTHS TO
JOSEPH M. WEBER, M. SHINE, F. MECKEL, AND RICHARD BOCHTLER,
OF SAME PLACE.

RAILWAY-BUFFER ARRESTER.

SPECIFICATION forming part of Letters Patent No. 581,185, dated April 20, 1897.

Application filed March 7, 1896. Serial No. 582,281. (No model.)

To all whom it may concern:

Be it known that I, JOHN A. WEBER, a citizen of the United States, residing in Chicago, Cook county, State of Illinois, have invented
5 a new and useful Improvement in Railway-
Buffer Arresters, of which the following is a
full, clear, and exact specification.

My invention relates to certain improvements
10 in a railway-buffer arrester, a patent
for which was duly granted to me on the 25th
day of February, 1896, and numbered 555,273,
and relates more particularly to the use of
15 the arresters at the end of those tracks com-
monly used for passenger service, although
the same may be found desirable for use in
freight service.

The patent to which reference has just been
made sets forth and describes an arrester
having a stationary post and another post
20 hinged thereto, the latter receiving the forcible
impact and moving upon its hinge in order
to relieve the strain. In moving upon
its hinge the movable post at its upper portion
25 travels through the arc of a circle, and
should the draw-head of the car impact and
bear directly upon the movable post these
parts must frictionally yield or the car would
be raised slightly from the track as the movable
30 post travels through the arc of a circle.
The object of this my invention is to over-
come the necessity of a frictional yielding and
tendency to raise the impacting car from the
track and to provide means whereby the draw-
35 head impacts against an object which yields
in the direct line of travel of the draw-head
and to accomplish this result without inter-
fering with the free movement of the hinged
post on its pivot.

My invention has certain other objects in
40 view; and it consists in certain features about
to be described, reference being now had to
the accompanying drawings, in which—

Figure 1 is a sectional plan view on the line
45 $x-x$ of Fig. 2, and Fig. 2 is a vertical section
on the line $y-y$ of Fig. 1.

The stationary post A is held in a fixed position
between the rails and at the end of the track
by any suitable means. To this stationary post
is hinged the movable post B,

which movable post is thus adapted to receive
50 the preliminary shock of the forcible impact
and relieve the same by a rearward movement,
its upper portion describing the arc of a circle whose center is at the point of hinging of the two posts.

Extended loosely through the two posts A
and B is the pull-rod D, having the two sets
of springs D² and D³ coiled around it and in-
terposed, respectively, between the faces of
the posts A and B and the holding-plates D⁴ on
60 the ends of the rod D, these springs serving
to return the movable post B into a normally
extended or advanced position to receive the
impact of the car and acting in opposition to
the rearward movement of the upper portion
65 of said post B.

In order that the draw-head of the car may
strike against an object or abutment inde-
pendent of the movable post A, I provide the
independent buffer-block J, which is disposed
70 or positioned in advance of or beyond the
front face of the movable post B. This buf-
fer-block J is held in position by means of the
buffer-block rod J², on the outer end of which
it is fixedly mounted, the rod J² extending
75 through or nearly through the two posts A
and B. An extending spring J³ is interposed
between a plate J⁴ on the end of the rod J²
and a cap J⁵, held on the rear of the post A.
The rod J² passes through an enlarged open-
80 ing in or perforation through the movable
post B, (designated at J⁶), and the pull-rod
D also extends through a like perforation J⁷.

When the buffer-block J receives the blow
from the draw-head of the advancing car or
85 other vehicle moving along the track, the
strain or stress of the shock is received by
said buffer-block J initially and transmitted
to the movable post B, the spring J³ also serv-
ing as a cushion for the shock. The movable
90 post B at its upper and lower portions in its
movements travels in the arc of a circle on
its hinge. It will be observed that by the
construction described the buffer-block J and
its rod J² may have a direct inward and out-
95 ward movement along a horizontal plane en-
tirely independent of the vibratory movement
of the movable post B, and as the draw-head

of the car impacts against the buffer-head J said buffer-head and its rod have a direct horizontal inward movement in the same direction as that of the thrust of the draw-head, 5 thereby avoiding any tendency to lift the car from the track.

Having thus described my invention, what I claim as new therein, and desire to secure by Letters Patent, is—

- 10 1. A buffer-arrester for railway-tracks consisting of a stationary post, a movable post hinged to the stationary post and a buffer-block mounted on the stationary post and held in advance of the stationary post which buffer-block has a movement independent of that of the movable post whereby the movable post may travel in the arc of a circle and the buffer-post in the direction of travel of the impacting object.
- 15 2. A buffer-arrester for railway-tracks consisting of a stationary post, a movable post hinged to the stationary post, a buffer-block, supporting arms or rods mounted on the stationary post holding the buffer-block in advance of the movable post whereby said buffer-block has a movement independent of that of the buffer-post and resisting means acting in opposition to the movement of the movable post adapted to restore the movable 25 post and the buffer-block into a position
- 30

whereby to again receive the impact of an object advancing along the track.

3. A buffer-arrester for railway-tracks consisting of a stationary post, a movable post hinged to the stationary post, a buffer-block, 35 a buffer-rod extended through the said posts carrying the buffer-block and holding the same in a position in advance of the movable post and a resisting device acting against the rearward movement of the buffer-block when the same receives the impact of an object moving along the track and means for restoring the movable post to an advanced position.

4. A buffer-arrester for railway-tracks consisting of a stationary post, a movable post 45 hinged to the stationary post, a buffer-block, a buffer-block rod which passes loosely through an enlarged opening in the movable post and a resisting device for said buffer-block adapted to extend the same into an advanced position together with means for normally holding the upper portion of the movable post in an advanced position.

In testimony whereof I have hereunto affixed my signature in the presence of two 55 witnesses.

JOHN A. WEBER.
